UNITED STATES PATENT OFFICE.

THOMAS WOLSTENHOLME, OF PHILADELPHIA, PENNSYLVANIA.

SHIELD OR DEFLECTOR FOR DRAWING-ROLLERS.

SPECIFICATION forming part of Letters Patent No. 607,724, dated July 19, 1898.

Application filed March 18, 1897. Serial No. 628,193. (No model.)

To all whom it may concern:

Be it known that I, THOMAS WOLSTENHOLME, a citizen of the United States, residing in Philadelphia, Pennsylvania, have invented a Shield or Deflector for Drawing-Rollers of Spinning-Machines, of which the following is a specification.

My invention relates to machinery used for spinning textile fibers, such as wool, cotton, silk, and the like; and it consists of a device for preventing the "licking in" of strands of the partially-twisted yarn during the process of spinning.

My invention is fully illustrated in the accompanying drawings, in which—

Figure 1 is a cross-section of the drawing-rollers of a spinning-mule, showing in connection therewith a device in accordance with my invention. Fig. 2 is a front elevation of sufficient of the drawing-rollers of the mule to illustrate the application of said device thereto. Fig. 3 is a view illustrating a modification, and Fig. 4 is a view illustrating another device for carrying out my invention.

It is well known among manufacturers of fine-spun yarn that loose ends or strands of the partially-twisted yarn as it emerges from between the drawing-rollers are caught by the lower fluted or ribbed drawing-roller and carried thereby down to the rotating under-cleaner, a cloth-covered roller situated beneath the outer fluted roller, the strands becoming wrapped or wound around said under-cleaner. This "licking" or "lapping" of the strands may be caused by a certain amount of electricity generated between the fluted roller and the twisted yarn or may be due to humidity or other atmospheric conditions and is a source of loss in a spinning-mill which it has been found impossible hitherto to prevent.

My invention consists of means for preventing the licking in of these loose strands by the fluted roller and in one form comprises a bar of metal or other suitable material mounted contiguous to but not touching the outer fluted roller, so that it will serve as a shield or deflector for loose fibers or strands drawn down by the fluted roller, or the device in another form comprises a hollow bar or pipe perforated or slotted to direct a jet or jets of air upwardly in proximity to the face of the

roller, so as to direct the strands or fibers away from the same.

In the drawings, A represents the roller-stand, supporting the drawing-rollers a a' a^2 a^3 . Above this roller-stand are mounted a series of arms B, having guideways b for the reception of the spindles d of the back roller D and the carrier-rollers D' and D². The parchment-roller D³, mounted above the front bottom fluted roller, is lighter than the other rollers, and to impart the necessary pressure to the yarn as it passes between this roller and the front bottom fluted roller a saddle E rests upon the spindle of the roller D³, and to this saddle is attached the weighted stirrup E'.

The rollers hereinbefore described constitute the well-known form of drawing-rollers common to spinning-mules, and underneath the front bottom fluted roller is the ordinary revolving under-cleaner H, supported in place adjacent to the front bottom fluted roller and adapted to clean said fluted roller of all strands that may have been caught by the same, this roller being mounted in suitable notches in the ends of the weighted levers F, pivoted at f.

Mounted in front of the lower fluted drawing-roller a is a bar G, which constitutes the subject of my invention and which acts as a shield or deflector for engaging the fibers or strands which would otherwise be carried down by the roller a to the under-cleaner and directs said fibers or strands away from said lower fluted roller, so that they will be caught up by the yarn and twisted in with the same.

The bar G preferably has a straight inner face and a curved outer face, although it may be of any desired form not incompatible with the proper performance of its function, and it is mounted so that its upper edge is located substantially in a horizontal plane passing through the center of the lower fluted drawing-roller and is in close proximity to the periphery of said roller, but not in actual contact therewith.

As there is always a certain amount of dust floating around a spinning-mule and as there are also some short small particles of yarn constantly dropping off the twisted roving, it is preferable to make the bar with smooth rounded outer surface, because such a con-

struction will prevent to the greatest extent such dust and particles from lodging thereon, and by mounting the bar vertically, so that its inner face and sharp edge will be parallel 5 or nearly parallel to the vertical diameter of the lower drawing-roller, this result is materially aided. Furthermore, during that time when the mule returns to allow the twisted yarn to be spun upon the cop there is little 10 or no danger of the yarn picking up dust or foreign material from the bar. However the bar G is mounted the sharp angle or knife-edge presented by the top of the same should be closest to the periphery of the roller, so 15 that there will be no likelihood of strands or fibers passing down between said upper edge and the roller.

The bar may extend along a series of sets of drawing-rollers, as shown in Fig. 2, and its 20 opposite ends may be dropped into sockets formed in brackets J, mounted upon the roller-stands A, or may be supported in any other available manner, but preferably so that it may be readily lifted out of or readjusted to its place, as circumstances may require.

If desired, the shield or deflector-bar may be carried by the levers F, which carry the under-cleaner, as shown in Fig. 3, the contact 30 of said under-cleaner with the lower fluted roller serving to limit the approach of the bar G toward the front of said roller, or any other available form of stop being used for the purpose.

35 In spinning the coarser grades of yarn I may use either alone or in addition to the shield or deflector G an air-current for the purpose of directing loose strands or fibers away from the periphery of the roller a. For 40 instance, as shown in Fig. 4, I may make the bar G' hollow and slot or perforate the upper edge of the same, so that a current of air will be directed upward across and in contact with the forward face of the roller a, thereby directing upwardly and outwardly away from the same any loose fibers or strands which might otherwise be carried down by said roller and be caused to engage or lap around the under-cleaner. The air-current in this case 45 acts in addition to the bar G, which performs its function, as before; but the air-current alone may be used, if desired, such current being derived from a perforated or slotted pipe so located in respect to the roller a as to 50 give said air-current its proper direction.

Having thus described my invention, I claim and desire to secure by Letters Patent—

1. The combination in a spinning-machine, 55 of a pair of drawing-rollers and an under-cleaner in contact with the lower drawing-

roller, with a sharp-edged bar mounted in front of but not touching the lower roller, and so located with respect to the lower drawing-roller that its sharp edge is substantially 65 in a horizontal plane passing through the center of said drawing-roller, and serving as a shield or deflector whereby the loose fibers or strands from the partially-twisted yarn emerging from between the rollers are 70 directed away from the periphery of the lower drawing-roller, substantially as described.

2. The combination in a spinning-machine, of a pair of drawing-rollers and an under-cleaner in contact with the lower drawing- 75 roller, with a sharp-edged bar having a straight inner face and a curved outer face, said bar being mounted vertically in front of but not touching the lower drawing-roller, and so disposed with relation to the said 80 drawing-roller that its sharp edge is substantially in a horizontal plane passing through the center of the lower drawing-roller, and serving as a shield or deflector whereby loose strands from the partially-twisted yarn emerging from between the rollers are 85 directed away from the periphery of the lower drawing-roller, substantially as described.

3. The combination in a spinning-machine, of a pair of drawing-rollers, and an under-cleaner 90 in contact with the lower drawing-roller, with a sharp-edged bar having a smooth outer face mounted vertically in front of but not touching the lower drawing-roller and having its upper edge closest to the periphery of said lower roller and disposed substantially in a horizontal plane passing through the center of said lower roller, so as to deflect loose fibers or strands away from 95 said periphery, substantially as described. 100

4. The combination in a spinning-machine, of a pair of drawing-rollers, an under-cleaner, 105 bearings for the same, weighted levers carrying the under-cleaner for keeping it in contact with the lower drawing-roller, and a bar carried by the outer ends of the weighted 110 levers and disposed in front of the lower drawing-roller and serving as a shield or deflector whereby loose strands from the partially-twisted yarn emerging from between the rollers are directed away from the periphery of said lower roller, the contact of said under-cleaner with the lower drawing-roller serving to limit the approach of the bar toward the same, substantially as specified. 115

In testimony whereof I have signed my name to this specification in the presence of two subscribing witnesses.

THOMAS WOLSTENHOLME.
